UNITED STATES PATENT OFFICE.

ETHELBERT M. FRASER, OF YONKERS, NEW YORK.

STARTING AND LIGHTING APPARATUS.

Specification of Letters Patent. Patented Dec. 31, 1918.

1,289,148.

Application filed August 14, 1917. Serial No. 186,088.

To all whom it may concern:

Be it known that I, ETHELBERT M. FRASER, a citizen of the Dominion of Canada, residing at Yonkers, county of Westchester, and State of New York, have invented new and useful Improvements in Starting and Lighting Apparatus, of which the following is a specification.

My invention relates to a starting and lighting apparatus particularly adapted for use in motor vehicles, although it is likewise applicable in other instances as will more fully appear from the following description.

One of the objects of my invention is to provide in a single unitary structure a motor-generator set comprising a stationary field structure, a rotatable armature, and an independently rotatable second winding interposed between said field structure and said armature, that can be utilized for generating electric current and used as a motor for starting automobiles.

Other objects of my invention will clearly appear from the drawings and from the detailed description to follow.

An apparatus embodying my invention is illustrated in the accompanying drawings, forming a part of this specification, in which—

30 Figure 1 is a side view partly in section.

Fig. 2 is a view illustrating the manner in which my improved starting and lighting apparatus may be connected up with a gasoline engine as used in motor vehicles.

35 Fig. 3 is a wiring diagram of my starting and lighting apparatus in connection with a starting switch, an automatic switch, a battery, lights, and horn motor.

Fig. 4 illustrates a portion of the rotatable 40 second winding shown in section.

In the preferred form of my device the improved starting and lighting apparatus comprises an outer stationary field structure B, an inner rotatable armature C and an intermediate independently rotatable second winding D, these three members constituting a motor-generator.

As shown in Fig. 1, the outer stationary field structure B comprises the magnet yoke 50 E, magnet cores and poles F, series coils G and shunt coils H, constituting one set of field magnets and coils. Secured to the magnet yoke E are the end-bells I and I', the central portions of which are constructed so

as to form hubs or bearings in which the 55 shafts J and J', respectively, are suitably journaled.

The rotatable armature C comprises the core K, the armature winding L and the commutator M. The armature C with its 60 commutator M is keyed or otherwise suitably secured to the shaft J.

The intermediate rotatable second winding D is made up of conductors of high 65 electric and magnetic conductivity, so constructed and arranged as to form a single winding, provided with a commutator N which is carried by the end-bell U which is keyed or otherwise suitably secured to the shaft J'. This end-bell U also forms a support and bearing for one end of the shaft J. The other end of the armature winding D is secured to but insulated from the end-bell P which is rotatably mounted upon the hub of 70 the end-bell I.

In Fig. 4 I have illustrated in section a part of this second winding D in which a is the soft iron portion made up of iron laminae, and b and c form the copper conductors, the conductors b and c being insulated from 80 each other and from the iron portion a by the insulation d.

Suitably secured to the hub of the end-bell I are the brushes O for the commutator M and suitably secured to the end-bell I' are 85 the brushes R for the commutator N.

As shown in Fig. 2 my starting and lighting device may be suitably secured to the casing of the gasoline engine S by means of the strap T, although if preferred it may be secured to the engine bed or to any other adaptable part of the motor vehicle. One end of the driving shaft S' of the engine S is connected by suitable gears and chain to the shaft J while the shaft J' may be provided with any suitable form of throw-out gear. Such a throw-out gear may be the well known "Bendix gear" which I have illustrated diagrammatically in Fig. 2, from 90 which it will be apparent that as the shaft 95 J' is rotated the pinion V will move forward to engage and rotate the toothed fly wheel W, thereby rotating the driving shaft of the engine S. In my improved starting and lighting apparatus the speed ratio between 100 the engine shaft and shaft J is preferably 2 to 1 while the speed ratio between the engine shaft and shaft J' is preferably 20 to 1.

105

Fig. 3 is a wiring diagram of my device as connected up with the starting switch X, the storage battery Z, the switch Q for opening or closing the battery circuit while the apparatus is generating electric current, the lights 1, 2 and 3, and the horn motor 4. The motor series coils G are shown in black heavy lines connected through the motor winding D to the starting switch X and to the storage battery Z. The generator shunt field coils H which are connected in shunt across the generator armature winding L are shown in light lines in the circuit of which is inserted the switch Q for automatically closing the circuit when the current has reached a certain voltage for charging the battery Z and which will open automatically when the voltage falls below the said predetermined amount. The lights 1, 2 and 3 and the horn motor 4, with their respective switches, are connected across the battery circuit.

With my improved starting and lighting apparatus connected in the manner shown in Fig. 2 the closing of the switch X will place the battery Z in circuit with the motor winding D and the series coils G. This will cause the winding D and the shaft J' to rotate; the pinion V will move out on its threaded shaft so as to engage and rotate the fly wheel W thereby causing the shaft of the engine S to rotate and start the engine. As soon as the engine speeds up sufficiently so that the fly wheel W causes the pinion V to rotate faster than the shaft J', the pinion V will automatically disengage the fly wheel W and the opening of the switch X will then cut out the motor winding D and series field coils G. The continued rotation of the shaft of the engine will rotate the shaft J and the armature C. The armature C with its co-operating field structure B will then act as a generator to generate current. When this current has reached a certain voltage the switch Q will close thereby enabling the battery Z to be charged. If the voltage generated by my device should fall below the predetermined amount then the switch Q will open thereby protecting the battery Z from any discharge. With an apparatus and system arranged in accordance with my invention the battery Z may be utilized for operating incandescent lamps in the various lights 1, 2 and 3 of the motor vehicle, or for operating the electric horn 4, or for supplying the energy for producing ignition in the cylinders of the engine or for any other adaptable purpose.

The improvements herein set forth are not limited to the precise construction and arrangement shown and described, for they may be embodied in various forms and modifications without departing from the spirit and scope of my invention.

What I claim is:

1. The combination with an explosive engine having a driving shaft, of a field structure having field magnets and coils, two armature windings which can move relative to each other, an armature core which is the only core for said armature windings and magnetically common to both, means intermediate said shaft and one of said armature windings connecting the two members together, and means for connecting and disconnecting said other armature winding to and from said shaft. 75

2. The combination with an explosive engine having a driving shaft, of a stationary field structure having one set of field magnets and coils, a rotatable armature provided with windings, core and commutator, an independently rotatable second winding interposed between said field magnets and 85 armature and concentric therewith, said core being the only core magnetically common to said armature windings and said second winding, means mechanically connecting said shaft with said armature, and 90 means for mechanically connecting and disconnecting said second winding to and from said shaft. 95

3. The combination with an explosive engine having a driving shaft, of two independently rotatable shafts, a stationary field structure having a set of field magnets and coils, an armature with its core and commutator suitably secured to one of said rotatable shafts, a second winding interposed 100 between said field magnets and said armature and concentric therewith, said second winding with its commutator being secured to the other of said rotatable shafts, means mechanically connecting said engine shaft 105 with said armature shaft, and means automatically putting said second winding shaft in and out of engagement with said engine shaft. 110

4. The combination with an explosive engine having a driving shaft, of a stationary field structure having one set of field magnets and coils, a rotatable armature with its core and commutator, an independently rotatable second winding interposed between said field magnets and armature and concentric therewith, said core being the sole core for said interposed second winding, a storage battery, a starting switch in series with said battery, said field coils and said second winding, means mechanically connecting said engine shaft with said armature, and means for mechanically connecting and disconnecting said second winding to and from said engine shaft. 115 120

5. The combination with an explosive engine having a driving shaft, of a stationary field structure having one set of field magnets, each magnet being provided with two coils, a rotatable armature with its core, an 125 130

- independently rotatable second winding interposed between said field magnets and armature and concentric therewith, said core being the sole core for said interposed 5 second winding, a storage battery, a starting switch in series with said second winding, with said battery and with one of said coils on each field magnet to form a motor coils on each field magnet to form a motor 10 circuit, the other coils on said field magnets being in shunt with the armature circuit to form a generator circuit, a switch adapted to open or close said generator circuit when the voltage therein falls below or exceeds a predetermined voltage, means mechanically connecting said engine shaft with 15 said armature, and means for connecting and disconnecting said second winding to and from said engine shaft on the closing or opening of said starting switch.
- 20 6. The combination with an explosive engine having a driving shaft, of an electric motor-generator comprising an outer stationary field structure, an inner rotatable armature, and a rotatable second winding 25 interposed between said field structure and said armature, means for transmitting the rotation of said second winding to said engine shaft at a suitable speed ratio, and means for transmitting the rotation of said 30 engine shaft to said armature at a suitable speed ratio.
7. A starting and lighting system comprising in combination an electric motor-generator having a motor shaft, a generator shaft, a field structure provided with field magnets and coils, two armature windings each provided with its own commutator and brushes, and one armature core which is magnetically common to both armature windings, one of said armature wind- 35 ings being interposed between said field magnets and said other armature winding and secured to said motor shaft, the other of said armature windings with its commuta- 40 tor and said armature core being secured to said generator shaft, a battery in the motor and generator circuits of said motor-generator, a switch adapted to open or close said motor circuit, and a switch adapted to automatically open or close said generator 45 circuit when the voltage therein falls below or exceeds a predetermined voltage.
8. The method of starting an engine and of generating electric current by means of an apparatus consisting of a stationary set of field magnets and coils, a rotatable armature provided with windings, core, commutator and brushes, and an independently rotatable current-carrying winding interposed 50 between said field magnets and said armature and having a commutator and brushes but no core, which method consists in passing an electric current through the field coils to produce a magnetic flux, simultaneously passing a current through said current-carrying winding to cause said winding to rotate, transmitting the rotary motion of said current-carrying winding to the driving shaft of an engine to start the 55 same, and transmitting the rotary motion of said engine shaft to the armature whereby the current set up in said armature reacts with said magnetic flux to produce electric 60 current.
- 70 This specification signed and witnessed this 11th day of August, A. D., 1917.
- 75 ETHELBERT M. FRASER.
